UNITED STATES PATENT OFFICE.

ALONZO FALLS, OF LOWELL, MASSACHUSETTS, ASSIGNOR OF ONE-HALF TO
ALEXANDER G. CUMNOCK, OF SAME PLACE.

EVENING MECHANISM FOR DRAWING-HEADS.

SPECIFICATION forming part of Letters Patent No. 500,120, dated June 27, 1893.

Application filed February 6, 1893. Serial No. 461,087. (No model.)

To all whom it may concern:

Be it known that I, ALONZO FALLS, a citizen of the United States, residing at Lowell, in the county of Middlesex and State of Massachusetts, have invented certain new and useful Improvements in Evening Mechanisms for Drawing-Heads, of which the following is a specification, reference being had therein to the accompanying drawings.

10 The object of my invention is to provide an improved construction and combination of parts constituting a new and useful improvement in evening mechanisms for drawing heads, which shall be simple and compact in 15 construction, durable, and reliable in operation.

20 My invention consists in certain novel features of construction and combinations of parts, all as fully set forth hereinafter, and first will be described with reference to the 25 accompanying drawings, and then will be particularly pointed out and clearly defined in the claims at the close of this specification which form a part hereof.

25 Figure 1 of the accompanying drawings is a view in side elevation of part of a drawing head with my invention applied thereto, enough of the drawing head being shown to make clear the relations and operation of my 30 improved devices. Fig. 2 is a view of the same in elevation from the right in Fig. 1. Fig. 3 is a view of the variable speed devices, showing them in vertical central section on the line 3—3 of Fig. 1. Fig. 4 is a view in rear 35 elevation of the yoke. Fig. 4^a is a view in end elevation of the yoke. Fig. 5 is a view thereof in vertical section on line 5—5 of Fig. 4. Fig. 6 is a face view of one of the measuring rods. Fig. 7 is a view thereof in side 40 elevation. Fig. 8 is a view thereof in horizontal section on the line 8—8 in Fig. 7. Fig. 45 9 is an enlarged view in plan representing the gearing by which the drawing rolls are connected with one another.

45 At 70 is shown the table of a drawing head, at 78, 78, are shown roll stands supported thereby, at F, M, 15 and 12 are shown the lower rolls supported by the said stands, at F², M², 159 and 129 are shown the top rolls resting on 50 the said lower rolls.

At F³ are shown fast and loose pulleys on

the lower front roll F receiving around the same the driving band whereby the said roll is rotated when the band is on the fast pulley.

55 At F⁴ is the gearing serving to transmit motion to rolls M and 12 from roll 15, the latter being driven as will be explained hereinafter.

At 76 is shown a stand for supporting the calender rolls, the latter being marked 19, 19. 60 At 193, 193 are shown the gears whereby the said calender rolls are caused to rotate in unison.

At 191 is shown a spur gear on the rear calender roll.

65 At I is shown a large gear meshing with the gear 191 and also with the gear F' on the lower front roll F and thereby serving for the transmission of movement from roll F to the calender rolls, and at 302 is shown the trumpet whereby the sliver issuing from between the front rolls is condensed and guided between the calender rolls.

70 All of the foregoing parts are or may be substantially as usual in drawing heads.

75 The roll 15 is provided with driving connections embracing variable-speed devices which are combined with controlling or governing devices that are acted upon by the material passing through the machine, the said controlling or governing devices operating to occasion an increase in the speed of rotation of the rolls 15, M and 12 when the slivers average too small or too thin, and the supply of material reaching the rear rolls becomes deficient, and to occasion a decrease in the speed 80 of rotation of the said rolls 15, M and 12 when the slivers average too large or thick and the supply of material reaching the rear rolls becomes 85 too great.

90 The variable-speed devices which I prefer to employ, and the preferred connections of such devices with roll 15, are such as those which are shown in the drawings. In the latter, the outer end of the lower roll 15 is 95 supported by a stand 781 and carries a bevel gear 152 meshing with a bevel gear 131 on a spindle 13, supported in an upright position by a stand 75 and stepped in a bearing formed in a transversely placed horizontal stud 73 100 which is supported in stands 74, 74 depending from table 70, the said bearing having a cover

731. The spindle 13 has placed thereon a sleeve 53 provided with a spline 531 fitted to a longitudinal groove 132 formed in the spindle, the said sleeve having affixed thereon a 5 disk or wheel 532 with its periphery faced with leather or other suitable frictional material 5321. Two bevel gear wheels 14, 14 are mounted on the stud 73 with capacity to turn freely thereon, the said wheels being located 10 on opposite sides of the spindle 13 and having their inner sides faced with leather or other suitable frictional material 141, 141. The disk or wheel 532 occupies a position between these gear wheels 14, 14, with the frictional material 5321 on its periphery in contact with the frictional material 141 covering the inner sides of the said wheels 14, 14. One of the said wheels 14, 14, is pressed against the periphery of the disk or wheel 532 by a 15 spiral spring 54 which surrounds the hub of the said wheel 14 and takes bearing at one end against the wheel and at the other end against the adjacent stand 74. The other wheel 14 may be similarly pressed if desired. 20 25 The teeth of both of the wheels 14 mesh with the teeth of an intermediately placed bevel gear 182 mounted on a suitably driven shaft 18, which in the drawings is shown placed in an inclined position and provided at its upper end with a bevel gear 181 that meshes with a bevel gear 192 on the rear calender roll 19. Thereby the said wheels 14, 14 are driven in opposite directions to each other, but at the same rate of speed. By the contact of the frictional material 5321 on the periphery of disk or wheel 532 with the frictional material 141 on the sides of wheels 14, 14, movement of rotation is communicated to spindle 13, and such movement is transmitted to rolls 15, M and 12 through the described connections.

The governing or controlling devices connect with the sleeve 53 by means of a loose collar 21 which is mounted on the exterior of 45 the sleeve between fixed collars 533, 534 on the sleeve, the said collar 21 having trunnions 211 that enter slots in the arms of the fork provided on one end of a lever 114. The said lever is moved on its pivot 1141 by the 50 governing or controlling devices, and carries with it the sleeve, moving the latter lengthwise of the spindle 13 so as to slide the disk or wheel 532 nearer to the axis of rotation of the wheels 14, 14 and reduce the speed transmitted through spindle 13 and the described 55 connections to the rolls 15, M and 12, or farther from the said axis so as to increase the said speed. As the said wheels 14, 14, are turned in opposite directions at a fixed rate 60 of speed by the driving connections described above, they communicate by frictional contact to the disk or wheel 532, rotation at a rate of speed which is proportional to the distance from their axis of rotation at which the said 65 disk or wheel bears against their inner sides.

The governing or controlling devices which move the lever 114 as the material passing to

the rolls varies in amount are as follows: At 71 is a stand secured to table 70 at a slight distance to the rear of the position of the rear 70 roll 12. The cross-piece at the top of this stand has a succession of rounded crests 711, 711 formed thereon at slight distances apart, and over this series of crests is extended a band or ribbon 50 of flexible, non-extensible material such as steel, which at the right-hand end thereof in Fig. 2 is connected to the stand 71 and at the left-hand end thereof, after passing partly around the pulley 10, is connected to one arm of lever 114, aforesaid. The pulley 10 is journaled to a lug extending laterally from a yoke 72 that is held to stand 71 by rivets 712, or screws. A series of so-called measuring rods 20, 20 is sustained in a position closely adjacent to the rear roll 12. The 80 feet of these rods rest upon the top of the steel ribbon 50 at points intermediate the crests 711, 711 of the stand 71, the lower ends of the said rods being placed between bars 721, 721 cast upon the yoke 72, one of such bars 90 standing on each side of the series of rods. The said lower ends are spaced apart and held in proper position over the spaces intermediate the crests 711, 711, by projections 202, 202, cast on their opposite edges. At the ends of 95 the series of rods these projections contact with the interior vertical faces of the stand, but intermediate such faces the projections of adjacent rods contact with one another. The heads 20, 20 of the rods have vertical slots 100 203, 203 with tapering passages 204, 204 leading thereto, and through these passages and slots pass the respective slivers on their way to the rolls. The distance from the bight of the rear rolls to the slots in the measuring 105 rods is made less than the length of the staple of the slivers, preferably, in order that the slivers may not become pulled apart or drawn out. The yoke has its top bar formed with a depending lip or flange 722 against which rest 110 the forward sides of the upper ends of the measuring rods as they are drawn forward by the friction of the moving slivers. On the said flange are provided guides 723, 723, which enter the slots 203 in the upper ends of the 115 rods 20. In the drawings each measuring rod 120 is formed on the forward side thereof with a projection extending beneath the flange 722, the upper surface of the said projection forming substantially a continuation of the curved 125 bottom of the slot in the rod. When the slivers are passing through the passages and slots in the measuring rods, and under the flange 722, the bulk of the cross-section of each sliver depresses the corresponding measuring 130 rod so as to cause the foot thereof to bend the steel ribbon down into the space between adjacent crests 711, 711. As the ribbon is thus bent by the rods the lever 114 is drawn upon so as to hold the disk or wheel 532 in a position between the wheels 14, 14 which is dependent upon the extent to which the ribbon is drawn upon in consequence of being bent. The parts are proportioned and arranged, as

will be understood, so as that so long as slivers of the desired given bulk continue to pass to the rolls, the rear rolls 15, M and 12 will be driven at a predetermined rate of speed. It will be obvious that when an increase takes place in one or more of the slivers so as to occasion an increase in the average bulk thereof, the corresponding rod or rods will be depressed to a greater extent by the increased volume of material passing through their slots and passages, thereby taking up more of the ribbon and drawing upon the lever 114 so as to shift the disk or wheel 532 inwardly between the wheels 14, 14, that is toward the axis of rotation of the latter, and causing a proportionate reduction in the speed of the rolls 15, M and 12. When a decrease in one or more of the slivers takes place so as to decrease the average bulk of the slivers the corresponding rod or rods will be permitted to rise or yield to the upward pressure of the ribbon, and the latter will be permitted to straighten somewhat and enable the disk or wheel 532 to be moved outwardly from the axis of rotation of wheels 14, 14, by the action of the spring 1142, thereby causing a proportionate increase in the speed of the rolls 15, M and 12.

By preference those parts of the governing or controlling devices which contact with the material passing through the machine are placed as shown in the drawings so as that the said material must meet and pass such parts before entering between the drawing rolls. It is advantageous thus to place the evening devices on the back instead of the front of the drawing head as formerly usual. Formerly, in most instances the trumpet through which the sliver passes on its way from the drawing rolls to the calender rolls was taken as the instrumentality for operating the evening mechanism. The sliver passing from the drawing rolls through the trumpet moves at about six times as high a rate of speed as it does at the point where it enters the drawing rolls, any unevenness in the sliver has an opportunity to pass before the evening devices have an opportunity to prevent it, and the sliver is drawn down to such an extent that a comparatively great difference in it must exist before the evener will work. By locating the devices which contact with the material in such position as that the latter must meet and pass the same before it enters between the rolls, the different parts of the evening mechanism are afforded opportunity to perform their office before the uneven part of the material has passed the drawing rollers, this result being facilitated by the slower travel of the material at this point in the machine.

I claim as my invention—

1. The combination with the rolls of a drawing-head, and roll-actuating mechanism embracing variable speed devices, of governing or controlling devices comprising a flexible band or ribbon connected with such variable

speed devices, and operating the latter by being itself drawn upon in the direction of its length in consequence of being flexed and a movable sliver guide acting upon the band or ribbon to occasion a flexure thereof proportionate to the size of the sliver and operating thereby to determine the speed transmitted to the rolls, substantially as described. 75

2. The combination with the rolls of a drawing-head, and roll-actuating mechanism embracing variable speed devices, of governing or controlling devices comprising a flexible band or ribbon connected with such variable speed devices, and operating the latter by being itself drawn upon in the direction of its length in consequence of being flexed and a series of movable pieces separately acted upon by individual slivers and acting upon the band or ribbon to produce flexures therein and operating thereby to determine the speed transmitted to the rolls, substantially as described. 80

3. The combination, with the variable speed devices, of governing or controlling devices comprising a flexible band or ribbon connected with such variable speed devices, a stand having a series of crests over which said band or ribbon extends, and a series of movable pieces separately acted upon by individual slivers and acting upon the band or ribbon at points intermediate the said crests, 95 substantially as described. 90

4. The combination, with the variable speed devices, of governing or controlling devices comprising a flexible band or ribbon connected with such variable speed devices, a stand having a series of crests over which said band or ribbon extends, a yoke having a depending flange, and a series of movable pieces separately acted upon by individual slivers and having surfaces between which and the said flange the said slivers are compressed, the said pieces acting upon the band or ribbon at points intermediate the said crests, 105 substantially as described. 100

5. The combination, with variable speed devices, of governing or controlling devices comprising a flexible band or ribbon connected with such variable speed devices, and operating the latter by being itself drawn upon in the direction of its length in consequence of being flexed and a series of movable pieces serving as guides for individual slivers and acting upon the band or ribbon as changes occur in the sizes of the slivers to determine the speed transmitted, substantially as described. 110 115

6. The combination, with variable speed devices, of governing or controlling devices comprising a flexible band or ribbon connected with such variable-speed devices, a stand having a series of crests over which said band or ribbon is passed, a yoke having a depending flange, and a series of movable pieces serving 120 125 as guides for individual slivers and having surfaces between which and the said flange the slivers are compressed, the said pieces 130

acting upon the band or ribbon at points intermediate the said crests, substantially as described.

7. The combination, with the rolls of a drawing head, and roll actuating mechanism embracing variable speed devices comprising a pair of driving wheels, means for rotating them at the same rate of speed but in opposite directions, an intermediate driven disk or wheel in frictional contact with the said wheels, a spindle in operative connection with the rolls, and on which said disk or wheel is splined, and a lever operatively connected with said disk or wheel for moving it on said spindle, of governing or controlling devices

comprising a band or ribbon connected with the said lever, and a series of movable pieces serving as guides for the individual slivers, the said movable pieces acting upon the band, or ribbon as they are moved by changes occurring in the sizes of the slivers to move the lever and shift the intermediate disk or wheel and thereby vary the speed transmitted to the rolls, substantially as described. 20

In testimony whereof I affix my signature in presence of two witnesses.
